ROLLER WEDGE DOOR HOLDER

Frank E. Andrews, Urbana, Ill., assignor of one-fourth to Abe Selcovitz, Urbana, Ill.

Application November 18, 1938, Serial No. 241,098

5 Claims. (Cl. 292—342)

This invention relates to improvements in door holders and stops for use in holding swinging doors of all kinds in any adjusted position.

The primary object of the invention is to provide a roller type door holder in which a roller, or rollers, is used to stop and hold the door and is so disposed that it will move slightly under the door to wedge the same in adjusted position but in such manner that injury to the floor or floor covering will be absolutely prevented.

Another object is to provide a door holder of this kind in which provision is made for the convenient replacement of the rollers so that a roller of a size suitable to any clearance between the door and floor may be used.

A further object is to provide a roller door holder of extremely simple and inexpensive form and which may be very conveniently operated to stop the door without stooping over to put it in place by hand.

These and other more specific objects of the invention will be made apparent in the course of the appended detailed specification, reference being had to the accompanying drawing, wherein:

Figure 1 is an elevation of one form of my improved door stop, showing the same as applied to a door and in door stopping position.

Figure 2 is an end view of the structure shown in Figure 1.

Figure 3 is an enlarged cross section of the roller mounting block with one side plate removed.

Figure 4 is a perspective view of another form of my invention, as applied to a door.

Figure 5 is an elevational view of the stop roller and supporting member employed in the structure of Figure 4.

Figure 6 is a side elevation of another form of my invention using several rollers of graded sizes.

Figure 7 is a top plan view of the device shown in Figure 6.

Figure 8 is an end view of still another embodiment of my invention.

Figure 9 is a top plan view of the device shown in Figure 8.

In carrying out my invention as exemplified in Figures 1, 2 and 3 of the drawing I provide for the conventional type of plunger door stop A, means for removably mounting a stop roller 10, so that this roller, instead of the usual stop foot, serves as the element engaging the floor and stopping the door. For this purpose the stop

assembly A, which is secured vertically to the door B by the screws C, has its plunger D provided with end plates 11 which are removably mounted by screws 12 on the ends of the plunger. These plates 11 are apertured to receive a pivot or journal member, or axle, 13 upon which the roller 10 is rotatably mounted to turn freely between the plates. The roller will, however, wedge or jam against the underside 14 of the plunger D, or rather between the plunger and the floor E, when the plunger is pushed downwardly and will thus act to secure the door against swinging movement at any desired position.

The use of a roller, instead of the usual foot or other rigid member, is of advantage in that a roller will provide a wedging action sufficient at all times to stop and hold the door without having any tendency to dig into, or otherwise injure the floor or covering thereof. In addition the use of a roller mounted as herein described makes it an easy matter to remove and replace the roller with another of another size in order to fit the device for use on a door hung at any usual level with respect to the floor line. The roller will also operate with equal effectiveness to stop the door against movement in either direction, due to its contact with the shoulders 15 at each side of the lower face of the plunger.

The stop assembly shown in Figures 4 and 5 again employs a roller 10a as the floor engaging element but in this case the roller is journaled on the inwardly turned pivot members or extremities 13a of a carrier or frame 16 which is made up from wire or other suitable material and is vertically movable in a bracket member 17 secured by screws 18 to the door B. The frame is of substantially inverted U-shaped form having the spaced sides or legs 19 which fit nicely within and frictionally engage the sides 20 of the bracket 17 and the upper bight portion of the frame is turned outwardly in the form of a loop or bight 21 which projects from the door and overlies the upper margin of the bracket to prevent the frame from falling. The parts are so proportioned that the roller 10a may drop to the floor E, when the loop 21 is pressed downward by the toe, and will then move slightly beneath the adjacent edge of the door B to exert a lifting and wedging action between the door and floor, sufficient to retain the door in adjusted position. The frame 16 has sufficient play, toward and away from the door, to enable it to swing as necessary for the roller to move beneath the door edge as will be

understood, and also the bracket is wide enough at its lower end 22 to receive and enclose the roller when the frame is raised by the toe. The legs of the frame may be readily spread apart 5 to free the roller from the pivot members 13a so that another roller of different size may be substituted, whenever this is necessary due to difference in the space between door and floor.

Figures 6 and 7 disclose another embodiment 10 of my invention wherein the stop assembly is made up of a plurality (for instance three) rollers 10b of graded or graduated sizes. These rollers are mounted on the spaced parallel pivot members or axles 13b which are mounted at 15 their ends in side bars or plates 23 and the assembly may be laid on the floor so that one of the rollers will wedge beneath the door and hold it in adjusted position. The use of several rollers of different diameters makes this device suitable for most any door, since one or the other 20 of the rollers will in most cases properly fit and wedge against the door.

Figures 8 and 9 show a structure comprising 25 two rollers 10c of equal size which are mounted on the two spaced and parallel pivot members or legs 13c of a wire frame 16c, which members are joined by the U-shaped or looped bight portion 21c offset upwardly as shown. The rollers are thus supported so that they may fit closely 30 beneath the two opposite edges of the door B and roll slightly therebeneath when the door is moved in either direction. The loop or bight portion 21c may be readily bent as necessary to spread or narrow the frame and cause the rollers to properly engage a door of any usual thickness.

The rollers may be made cheaply of wood or other suitable material having sufficient rigidity for the purpose but which is not liable to injure the floors.

From the foregoing it will be evident that I 40 have provided extremely simple and effective means for stopping and retaining a door in adjusted position and which may be readily adapted to any door. The devices are very conveniently 45 manipulated and are so constructed that mar- ring of either the door or the floor is absolutely prevented.

It is understood that I may vary from the 50 structure herein set forth, provided that such variations fall within the scope of the appended claims.

Having thus fully disclosed my invention, what I claim as new and desire to secure by Letters Patent, is:

55 1. A door holder for a door movable in spaced

relation with respect to a fixed surface, comprising a bracket carried by the door, a frame member vertically slidable in the bracket, a roller removably mounted at the lower end of the frame member and adapted, as the frame is lowered, to roll beneath the door and wedge the same with respect to said fixed surface and means for yieldably retaining the frame in an adjusted position in the bracket.

2. A door holder for a door movable in spaced 10 relation with respect to a fixed surface, comprising a bracket carried by the door, a frame member vertically slidable in the bracket, a roller removably mounted at the lower end of the frame member and adapted, as the frame is lowered, to 15 roll beneath the door and wedge the same with respect to said fixed surface, the said bracket being adapted at its lower end to receive the roller as the frame is raised.

3. A door holder for a door movable in spaced 20 relation with a fixed surface, comprising a bracket member carried by the door, a wire frame slidably mounted in the bracket member for movement toward or away from said surface, a roller carried at one end of the frame for wedg- 25 ing engagement between the door and fixed surface, and a loop portion of the frame being turned outward from the door for manipulat- ing the frame in said bracket member.

4. A door holder, comprising a bracket mem- 30 ber secured to a lower portion of the door ad- jacent the floor, a wire frame of inverted U- shaped form slidably mounted for movement in up and down directions in said bracket member, a roller carried between lower end portions of 35 the frame for wedging engagement between the door and the floor, and the said bracket having a lower opening to permit the frame and roller to move toward and away from the lower edge of 40 the door.

5. A door holder comprising a bracket member secured to a lower edge portion of the door ad- jacent the floor, a wire frame of U-shaped form 45 slidably mounted for movement in the bracket toward and away from the floor, the bight portion of the frame being turned outwardly and exposed for manipulating the frame, a roller removably mounted between lower end portions of the frame and adapted to move between the door and floor 50 to hold the door, and the said bracket member having a lower opening to receive the roller when the frame is moved upwardly in the bracket member.

FRANK E. ANDREWS. 55
